UNITED STATES PATENT OFFICE.

DANIEL B. LUTEN, OF INDIANAPOLIS, INDIANA.

OVERHEAD CROSSING.

1,334,872.

Specification of Letters Patent. Patented Mar. 23, 1920.

Application filed June 2, 1917. Serial No. 172,352.

To all whom it may concern:

Be it known that I, DANIEL B. LUTEN, a citizen of the United States, residing at Indianapolis, in the county of Marion and 5 State of Indiana, have invented a new and useful Overhead Crossing, of which the following is a specification.

It is the object of my invention to produce a reinforced concrete overhead railroad 10 crossing of general adaptability, of pleasing appearance, and of rigid and permanent structure at a minimum of expense for labor and materials.

The accompanying drawing illustrates my 15 invention in its preferred form. Figure 1 is an elevation, with one end in section, of a railroad crossing embodying my invention; Fig. 2 is a half plan of such crossing; Fig. 3 is a section on the line 3—3 of Fig. 1; Fig. 20 4 is a section on the line 4—4 of Fig. 1; and Fig. 5 is a section on the line 5—5 of Fig. 1.

There are two or more slender intermediate concrete piers 10, resting on suitable footings 11, and a concrete pier 12 at each end 25 of the structure, each end pier 12 preferably comprising two separated columns on suitable footings 13. A thin floor slab of concrete 14 extends, preferably continuously, from one end of the structure to the other, 30 over the end columns 12 and the intermediate piers 10, and carries a suitable roadway 15. A series of arch cantalivers 16, of concrete, rest on the piers 10 and columns 12 at each side of the roadway, and may be continuous 35 with the floor slab 14. The cantaliver arms from one pier abut against and may be continuous with those from the next pier. The cantalivers project above the floor slab, so as to produce a continuous coping, but are arch shaped on the under side so 40 that they project materially below the floor slab at and near the piers but are substantially flush with the under side of the floor slab midway between adjacent piers. Embedded 45 in the upper part of the cantalivers 16 are tension rods 17, which are continuous over the piers 10 and 12 substantially to the midway points between adjacent piers, and may be continuous for the whole length of 50 the structure if desired. Suitable railings 18, extending from one end of the structure to the other, are usually mounted on the cantalivers 16.

The arch cantalivers 16 and the piers 10 55 and columns 12 carry the floor slab 14. In order that they may do this, the floor slab

has embedded therein near its under surface a number of reinforcing rods 19 extending in oppositely oblique directions across the floor slab from one cantaliver 16 to the other, such rods being turned up into the cantalivers 16 at each side so that they project upward to or beyond the tension rods 17. By these oppositely diagonal rods 19, the load on any portion of the floor slab 14 is transmitted to the cantalivers 16 on both sides of the roadway, and this transmission is always in part to points on such cantalivers which are closer to the piers, or on the opposite side of a pier. Moreover, a load on the floor slab 14 at intermediate points between adjacent piers is transmitted by such oppositely diagonal rods 19 to the cantalivers 16 projecting from both adjacent piers, so that a double supporting action is obtained—if not a quadruple one 70 because of the cantalivers on both sides and from both adjacent piers, making four in all. By reason of this transmission of forces, the floor slab may be made very thin, and a minimum of material may be used in 75 the cantalivers. The continuity of the floor slab, and of the rods 19 from the cantalivers 16 on one side of the roadway from one pier to the cantalivers 16 on the other side of the roadway and in many cases from another 80 pier, brings all the nearby cantalivers into supporting relation to any part of the floor slab. This continuous structure is much stronger than simple cantalivers, because two piers operate to support a load on the floor 85 slab between them.

The cantalivers 16 projecting from the end columns 12 toward the fill 20 just clear such fill, to permit relative movement between them and the fill upon changes in temperature, thus avoiding the production of undue strains on the structure; but preferably these cantalivers 16 conform to the fill and are so close thereto that they produce the appearance of solid abutments. 100

In order to prevent rotation of the piers 10 or end columns 12 about their bases, or of the cantalivers 16 about the upper ends of such piers or end columns, such piers and columns have embedded therein vertical 105 reinforcing members 21 near both faces. These coöperate with the tension rods 17 in the cantalivers and the reinforcing rods 19 in the floor slab and cantalivers to prevent such rotation.

Frequently a railroad crossing when built has both ends up in the air, and the approach 110

fills are put in later; and these fills are subject to settlement, whereby an objectionable uneven joint is formed between the ends of the structure and the fill. Such unevenness 5 may also occur in the present structure by reason of the rise and fall of the free end cantalivers 16' on changes in temperature. To prevent such an uneven joint, regardless of such settlement or such rise and fall, 10 I provide at each end of the structure a cross beam 22, preferably provided with reinforcing rods 23 near its under face, and a cross beam 24 for embedment in the fill 20 when the latter is made, which cross beam has 15 upwardly extending lugs 25 at its ends; and extending from the cross beam 22 to the cross beam 24, and held from separation by the lugs 25 and the cantalivers 16, are a number of spanning beams 26, each of which has 20 one end resting on the cross beam 22, and pivotally interlocking therewith, as by an upwardly projecting rib 27 on the cross beam projecting into a groove in the lower face of the spanning beam 26. The spanning beams at 25 the sides of the roadway may have upwardly projecting flanges 28, which provide curbs. When settlement of the fill occurs, the spanning beams 26 tilt as required so as to maintain a substantially even roadway surface between the fill and the floor slab. By having 30 a plurality of separated spanning beams, unequal settlement is permitted and the spanning beams can be more readily molded and placed. The spanning beams 26 may be 35 molded when the structure is built, and left on the floor slab 14 until the fill 20 is made, and may then be put in place by the filling contractor, without requiring skilled labor, and preferably are covered with the roadway material to prevent wear on the concrete.

I claim as my invention:

1. An elevated crossing, comprising a series of piers, a plurality of series of arch cantalivers projecting from such piers toward adjacent piers, a concrete floor slab between the series of cantalivers, and reinforcing rods embedded in said floor slab near its under face and extending through the floor slab in oppositely oblique directions 45 from one series of cantalivers to another.

2. An elevated crossing, comprising a series of piers, a plurality of series of cantalivers projecting from such piers toward adjacent piers, a concrete floor slab between 50 the series of cantalivers, and reinforcing rods embedded in said floor slab near its under face and extending through the floor slab in oppositely oblique directions from one series of cantalivers to another.

60 3. An elevated crossing, comprising a series of piers, a plurality of series of concrete cantalivers projecting from such piers toward adjacent piers, a concrete floor slab between the series of cantalivers, and reinforcing

ing rods embedded in said floor slab near its under face and extending through the floor slab in oppositely oblique directions from one series of cantalivers to another, said cantalivers projecting both above and below the floor slab, and said reinforcing rods in the 70 floor slab being turned upward into said cantalivers.

4. An elevated crossing, comprising a series of piers, a plurality of series of concrete cantalivers projecting from such piers toward adjacent piers, a concrete floor slab between the series of cantalivers, and reinforcing rods embedded in said floor slab near its under face and extending through the floor slab in oppositely oblique directions 75 from one series of cantalivers to another, said cantalivers projecting both above and below the floor slab, and said reinforcing rods in the floor slab being turned upward into said cantalivers, said floor slab being 80 continuous between adjacent piers.

5. An elevated crossing, comprising a series of piers, a plurality of series of concrete cantalivers projecting from such piers toward adjacent piers, a concrete floor slab 90 between the series of cantalivers, and reinforcing rods embedded in said floor slab near its under face and extending through the floor slab in oppositely oblique directions from one series of cantalivers to another, 95 said floor slab being continuous between adjacent piers.

6. An elevated crossing, comprising a series of concrete piers, a plurality of series of concrete cantalivers projecting from such piers toward adjacent piers, a concrete floor slab between the series of cantalivers, reinforcing rods embedded in said floor slab near its under face and extending through the floor slab in oppositely oblique directions 100 from one series of cantalivers to another, and vertical reinforcing rods in said piers near both faces.

7. An elevated crossing, comprising a series of piers, a plurality of series of cantalivers projecting from such piers toward adjacent piers, a plurality of tension members embedded in concrete and extending in oppositely oblique directions from one series 110 of cantalivers to another, and a roadway supported on said oblique tension members.

8. An elevated crossing, comprising a series of piers, a plurality of series of cantalivers projecting from such piers toward adjacent piers, and a plurality of tension members embedded in concrete and extending in oppositely oblique directions from one series 120 of cantalivers to another.

9. An elevated crossing, comprising a series of piers, a plurality of series of cantalivers projecting from such piers toward adjacent piers, abutting cantalivers from adjacent piers being continuous, a concrete

floor slab between the series of cantalivers, and reinforcing rods embedded in said floor slab near its under face and extending through the floor slab in oppositely oblique 5 directions from one series of cantalivers to another.

10. An elevated crossing, comprising a series of piers, a plurality of series of cantalivers projecting from such piers toward adjacent piers, abutting cantalivers from adjacent piers being continuous, and a plurality of tension members embedded in concrete and extending in oppositely oblique

directions from one series of cantalivers to another.

11. In combination, a bridge having a cross beam at the end, and a plurality of separably movable spanning beams each having one end pivotally mounted on said cross beam and the other resting on the 15 approach fill.

In witness whereof I have hereunto set my hand at Indianapolis, Indiana, this 23d day of May, A. D. one thousand nine hundred and seventeen.

DANIEL B. LUTEN.
